AUXILIARY FEEDING MECHANISM FOR
SEWING MACHINES

Fritz Ebert, Oberndorf-on-the-Neckar, Germany

Application September 30, 1936, Serial No. 103,431
In Germany October 3, 1935

5 Claims. (Cl. 112—203)

The present invention is an improvement in sewing machines as disclosed by U. S. Patent No. 2,044,275 to Ernst Bucher.

In carrying out the method of producing a combined joining and covering seam as in said U. S. patent it has been found, that the fabric fed under a certain angle is distorted by the feed used hitherto and cannot be properly fed to the needle. This drawback is eliminated by the 5 present invention. To this end a specially formed auxiliary feed-dog is provided which is adapted to swing in a horizontal plane and has its engaging face formed at a desired inclined angle. The auxiliary feed-dog cooperates with a 10 portion of the auxiliary presser foot which is capable of yielding in a horizontal plane and which also is inclined under at a desired angle, so that by this arrangement the fabric is positively fed towards the first needle in a definite 15 position. It is important that both layers of the fabric be fed simultaneously until directly under the first needle, so that a safe piercing of the fabric is obtained and turning aside of the fabric is thereby prevented.

20 The auxiliary feed-dog is driven by the well known carrier bar of the usual feed-dog and at one side of said carrier bar an eye is provided and in which is arranged a guide pin for a sliding block which is in turn swingably arranged in 25 a sliding block lever. The front end of this guide pin is provided with a flange or collar engaging the sliding block lever. By this means not only is the reciprocating motion of said carrier bar transferred, but also the up and down 30 movements of same. The sliding block lever is fixed upon a shaft, mounted in the bearing block for the trimming mechanism, and this movement is transmitted to the feed-dog holder provided at the front end so that all movements of the auxiliary 35 feed-dog are derived from said carrier bar. The amount of differential movement may be adjusted in the well known manner.

The auxiliary presser foot cooperating with the auxiliary feed-dog is resiliently mounted to allow cross seams to pass. For the purpose of introducing the fabric the auxiliary presser foot may, however, also be pivoted simultaneously with the lifting of the normal presser foot for the main feed. For this purpose, a shaft is journaled at both front faces of the work support and upon one end of this shaft a lever is fixed engaging a chain which is connected to the lever serving to lift the normal presser foot. At the other side of the work support a lever is loosely 40 pivoted upon this shaft and this lever has the

special auxiliary presser foot pivotally mounted thereon. Moreover, this lever is provided with a cam or projection cooperating with a cam lever mounted and connected to said shaft. Hereby the auxiliary presser foot is swung out as soon as, during feeding of the fabric, the normal or usual presser foot is lifted by means of the pedal or a knee-lever. As soon as the pressure exerted upon the knee-lever or pedal is removed, the auxiliary presser foot returns again into its 10 working position under the action of a spring. Two springs act upon the auxiliary presser foot. The tension of these two springs may be regulated by means of screws which may easily be reached by a screw driver when a cover plate has 15 been swung outwardly upon its pivot.

One of these springs not only serves the purpose of returning the auxiliary presser foot to its working position after having been pivoted, but is also adapted to exert the proper pressure 20 suitable for the material being treated. This pressure of the spring may, as mentioned already, be regulated.

The pressure of the second spring is weaker, and this spring only acts, when a cross seam is 25 presented. The auxiliary presser foot is swingably arranged upon a pin, so that, as soon as a cross seam comes into the range of the auxiliary presser foot, the latter swings out, so that the spring is somewhat compressed and the front 30 end of the auxiliary presser foot only rests upon the cross seam, whereas the rear end bears against the fabric. By this swingable arrangement, the auxiliary presser foot may adapt itself automatically to the work as far as possible. 35 If for instance the cross seam reaches the rear end of the auxiliary presser foot, the latter is swung back and therefore at this time its front end is caused again to press upon the normal fabric layer. This is of greatest importance for 40 a cloth feed free of objections encountered heretofore with machines of the type aforesaid.

The axis or shaft carrying the auxiliary presser foot also serves as bearing for the cover plate. The latter is held in its closed and open positions 45 by a spring fixed to the bearing block by means of a screw and bearing against a square portion formed with said cover plate. The position of this cover plate may, therefore, easily be altered.

A slot is provided in the bearing block to laterally limit the cover plate. Against the one boundary wall of this slot bears the bearing member of the cover plate and against the other boundary wall the hub of the lever carrying the auxiliary presser foot. If the cover plate is 50 55

swung out, simultaneously the looper for drawing in the thread is rendered easily accessible. Below the auxiliary feed-dog and the resilient auxiliary presser foot, the two knives operate. It is of great importance to interrupt the cloth feed during trimming, so that the horizontally yielding auxiliary presser foot may press the lower part of the fabric edges against the edge of the fixed knife and the upper part of the fabric edges may bear against the edge of tongues adjustably fixed to the throat plate.

To allow for an adjustment of the width of the trimmed off portion, i. e., to prevent an unnecessary broad portion of the fabric being cut off and thereby to avoid waste of material, a guide, adjustably mounted in a longitudinal slot, is provided at the front side of the bearing block. This guide is provided with an index mark and may be adjusted from "0" to "10".

20 In the accompanying drawings, forming part of the specification, one construction according to the invention is shown by way of example.

In these drawings:

Fig. 1 is a perspective view illustrating the most important parts of a machine according to the invention,

Fig. 2 shows, also in a perspective view, the drive of the novel auxiliary feed-dog and also shows the different motions thereof,

30 Fig. 3 is a perspective view, showing the arrangement of the new auxiliary presser foot including the device for pivoting the same,

Fig. 4 is a perspective view of the throat plate, the bearing block, the guide and the feeding means,

Fig. 5 is a cross-sectional view, showing the manner in which the fabric is fed, held and trimmed,

Fig. 6 is a side elevation, partly in section and showing the resilient arrangement of the new auxiliary presser foot, and

Fig. 7 is an end elevation, partly in section, of the device illustrated in Fig. 6.

The drive and the adjustment of the carrier bar 1 for the normal feed-dog is obtained in a well known manner as in sewing machines of the aforementioned U. S. Patent No. 2,044,275, and does not form the subject matter of the present invention. At one side of the front end of carrier bar 1 of the normal feed-dog is formed a split eye 2 in which a guide pin 4 is fixedly mounted by means of a tightening screw 3 bringing the two portions of said split eye toward one another. Formed with and extending from said guide pin 4 is a sliding block 5 moving within a sliding block lever 6. Said sliding block 5 is provided on one end with a collar 7 which, with the aid of said guide pin 4 upon the opposite end of said sliding block 5, causes the longitudinal movement of carrier bar 1 to be transmitted to the sliding block lever 6. Said sliding block lever 6 is adjustably mounted at an angle from vertical upon a shaft 9. A bearing block 8 has said shaft 9 slidably and pivotally mounted therein. At one end of said shaft 9 outside of said bearing block 8 is adjustably mounted a feed-dog holder 10, which feed-dog holder 10 supports an auxiliary feed-dog 11, which is adjustable vertically thereon.

70 Said carrier bar 1 is normally given both vertical and horizontal reciprocations and, therefore, eye 2 imparts through guide pin 4 to sliding block 5 a vertical as well as a horizontal reciprocation. Inasmuch as sliding block lever 6 is mounted at an angle and said sliding block 5

moves vertically as well as horizontally, sliding block lever 6 is moved radially with respect to shaft 9 and, therefore, shaft 9 receives a pivotal movement which by connection imparts to auxiliary feed-dog 11 its work engaging and disengaging movements. The horizontal reciprocations of sliding block 5 impart through sliding block lever 6 to shaft 9 a horizontal reciprocation which in turn through feed-dog holder 10 imparts to auxiliary feed-dog 11 its feed and return strokes.

The auxiliary feed-dog 11 cooperates with a special auxiliary presser foot 13 which is pivotally mounted upon a pin 15 fixed in a lever 14.

The lever 14 is pivotally mounted upon a shaft 15 arranged in the work-carrying arm 16.

Another pin 18 engaging in a slot 19 of the auxiliary presser foot 13 and mounted in the lever 14 serves to limit the swinging movement of said presser foot 13. In a bore provided in the lever 14 a spring 20 is arranged bearing with one of its ends against a screw 21 adjustably mounted in the bore and with its other end against a downwardly directed projection 22 at the front portion of the auxiliary presser foot. By adjusting the screw 21 the pressure of the spring 20 may be regulated.

Below the spring 20 a stronger spring 23 is arranged in a recess of the lever 14 and this spring bears against a screw 24 fixed in a bore 30 provided in the bearing block 8 for resiliently holding the lever 14 in position. The pressure of this spring also may be regulated by adjusting the screw 24.

Fixed upon the shaft 17, Fig. 3, is a chain 35 lever 25 engaging a chain 26 serving to lift the normal or usual presser foot. Fixed to the front end of the shaft 17 is a cam lever 27, cooperating with a cam 28 provided on the lever 14. If the pedal or the knee-lever of the chain 26 is operated, the normal or usual presser foot is lifted, simultaneously the movement is also transferred to the lever 25 and thereby to the shaft 17. By means of the cam lever 27, the lever 14 is swung against the action of the spring 23 and space is thereby obtained at the auxiliary feed-dog 11 for introducing the fabric.

The two screws 21 and 24 may easily be reached by a screw driver after a cover plate 29 has been swung into its open position. The shaft 17 serves as pivot for the cover plate 29. The latter is provided with a bearing member 30 having a number of flat faces and is loosely pivoted upon said shaft 17. The bearing block 8 is provided with a slot in which the hub of the lever 14 and the bearing member 30 are arranged. The slot in the bearing block 8 thus forms the lateral limitation for this hub and bearing member. A spring 32, fixed to the bearing block 8 by means of a screw 31, bears upon a corresponding flat face of the bearing block 8 and thereby serves to hold the cover plate 29 in an open or closed position. A tongue 34 is adjustably fixed upon the throat plate 33. The tongue 34 mainly serves as cover plate for the auxiliary feed-dog 11 and simultaneously determines the piercing of the edges of the fabric fed under at a desired angle, because these edges are placed around this tongue and are pressed against this edge by means of the auxiliary presser foot 13.

The auxiliary presser foot 13 also presses the fabric edges against the fixed knife 35, so that the fabric is safely held during trimming, as at this time no feeding is effected by the auxiliary

feed-dog. A guide 37, adjustably fixed in a longitudinal slot 36 by a screw 38, is provided at the front end of the bearing block 8 in order to allow adjustment of the width of the portion 5 to be cut off, which width, by the arrangement described above and serving to safely guide the fabric during trimming, may now be considerably smaller. The guide 37 carries an index mark 39 cooperating with a scale 40 provided at the bearing block 8. By a corresponding adjustment which may be exactly fixed by the scale 40, a portion as small as possible may be trimmed off, whereby a considerable amount of material is 10 saved.

15 What I claim is:

1. An improvement in a sewing machine of the character described comprising in combination an auxiliary feed-dog, means giving said auxiliary feed-dog a reciprocal feeding motion comprising an eye provided at one side of the normal feed bar of said sewing machine, a guide pin mounted in said eye, a sliding block provided on said guide pin, a sliding block lever having said sliding block workably mounted therein, a 20 collar on said sliding block for retaining said sliding block in said sliding block lever, means connecting said sliding block lever with said auxiliary feed-dog, and an auxiliary presser foot having a pressing surface on one side thereof 25 inclined at a desired angle resiliently mounted for yielding horizontally and for cooperating with said auxiliary feed-dog.

2. An improvement in a sewing machine of the character described comprising in combination an auxiliary feed-dog mounted for swinging horizontally, means in conjunction with said sewing machine for operating said auxiliary feed-dog, and an auxiliary presser foot, a lever resiliently and pivotally carrying said auxiliary 30 presser foot, means for operating said lever simultaneously with the raising of the lifting means for the normal presser foot of said sewing machine and a spring for returning said lever into its operative position upon relief of the pressure 35 on said lifting means.

40 3. An improvement in a sewing machine of the character described comprising in combination an auxiliary feed-dog mounted for swinging horizontally, means in conjunction with said sewing

5 machine for operating said auxiliary feed-dog, and an auxiliary presser foot, a lever carrying said auxiliary presser foot, said lever having a projection formed therewith, a cam lever cooperating with said projection, a shaft supported by 5 the work-carrying arm of said sewing machine and having said cam lever mounted thereon, and means operatively connecting said shaft with the pedal for lifting the usual presser foot of said sewing machine in order that both of said presser 10 feet may be moved for introducing fabric to said sewing machine when desired.

4. An improvement in a sewing machine of the character described comprising in combination an auxiliary feed-dog mounted for swinging horizontally, means in conjunction with said sewing machine for operating said auxiliary feed-dog, and an auxiliary presser foot, a lever pivotally mounted within the work-carrying arm of said 15 sewing machine and having said auxiliary presser 20 foot pivotally mounted on the free end thereof, said auxiliary presser foot having a projection formed therewith, a spring mounted within said lever and adapted to bear against said presser 25 foot projection, a second spring mounted within 30 said work-carrying arm and adapted to bear against said lever in opposition to said first spring, and a screw for each of said springs mounted for regulating the tension of said springs.

5. An improvement in a sewing machine of the character described comprising in combination an auxiliary feed-dog, means giving said auxiliary feed-dog a reciprocal feeding motion comprising a bearing block provided at the free end 35 of the work-carrying arm of said sewing machine, a shaft journaled in said bearing block, a sliding block connected to the normal feed bar of said sewing machine for receiving vertical reciprocation, a sliding block lever having said sliding 40 block workably mounted therein and mounted upon said shaft at an angle from vertical, a holder having said auxiliary feed-dog adjustably mounted thereon and fixed to said shaft, and an auxiliary presser foot resiliently mounted for 45 yielding horizontally and for cooperating with said auxiliary feed-dog.

FRITZ EBERT.
